United States Patent Office.

LOUIS RINGLER, OF NEW YORK, N. Y.

Letters Patent No. 92,544, dated July 13, 1869.

IMPROVEMENT IN IRONING-MACHINE.

The Schedule referred to in these Letters Patent and making part of the same.

To all whom it may concern:

Be it known that I, LOUIS RINGLER, of the city of New York, in the county and State of New York, have invented a new and improved Ironing-Machine; and I do hereby declare that the following is a full, clear, and exact description thereof, which will enable others skilled in the art to make and use the same, reference being had to the accompanying drawing, forming part of this specification, in which—

Figure 1 represents an end elevation of my improved ironing-machine.

Figure 2 is a side elevation, partly in section, of the same.

Figure 3 is a detail side view, on an enlarged scale, of the seam-ironing attachment.

Figure 4 is a detail transverse section of the same, taken on the plane of the line $x-x$, fig. 3.

Similar letters of reference indicate corresponding parts.

This invention relates to a new machine for ironing pantaloons and other garments, and for smoothing the sewed seams of the same.

The invention consists in the application of two smoothing-tubes, of which one is made to revolve, while the other can be moved laterally in its slotted bearings. The garment to be smoothed is placed between and over these tubes, and drawn or pulled forward, so that it will be smoothed as it rotates the upper tube. The tubes are heated by gas, steam, or otherwise.

The invention consists, also, in the application of a ring to the lower tube, said ring carrying a projecting lug, by which the seams can be ironed, as hereinafter more fully described.

A, in the drawing, represents the frame of my improved ironing-machine.

B and C are two horizontal tubes, supported on the frame. These tubes enter a reservoir, D, which is supported on the frame A, or on a separate frame, and which receives a gas-pipe, a , or a steam or hot-water supply, or is otherwise heated. The heat created in this reservoir passes into the pipes or hollow cylinders B C, and heats the same.

The upper cylinder, B, is hung loosely in its bearings, so that it can easily revolve. The other cylinder,

C, cannot revolve, but has a lateral motion, its outer end, b , fitting through and moving in a horizontal slot of the frame A, so as to be placed diagonally to the direction of the cylinder B, although it will, by a suitable spring, c , be held directly under B.

The swinging end of the pipe C is, by means of a cord, d , which passes over pulleys h h , connected with a lever, E. By pressing upon said lever, the pipe C will be drawn to its diagonal position, as aforesaid.

The pantaloons or other article to be ironed is, when the pipe C is drawn to its diagonal position, placed between the two pipes. The lever is released, and the spring c will then draw the pipe C under B, and the garment is bent over B, and drawn between the two cylinders. It will then cause B to roll, and will, by being in contact with both cylinders, be ironed on both sides.

A collar, e , is fitted around the cylinder C, and is loose thereon, so as to be turned in either direction. It has a projecting lug or ear, f , and can be locked in proper position by a set-screw, g . The collar is so adjusted that its lug is in a suitable position, and then the seam of the garment is placed over the lug, as indicated in fig. 4, and pulled through between the cylinders. The seam will thereby be ironed, and the two flaps of cloth flattened down.

Having thus described my invention,

What I claim as new, and desire to secure by Letters Patent, is—

1. An ironing-machine, consisting of the hollow cylinders B C, one revolving in a fixed position or bearings, and the other having a lateral motion at one end in the slotted frame, by means of a cord, d , lever E, and spring c , substantially as herein shown and described, to operate as set forth.

2. The seam-ironing attachment, consisting of the collar e , which has the projecting lug f , adjustable to a fixed position on the cylinder C, by means of the set-screw g , substantially as herein shown and described, to operate as set forth.

LOUIS RINGLER.
